CLAIM

The ornamental design for a package for container, as shown and described.

DESCRIPTION

FIG. 1 is a perspective view of the package for container showing the new design.

FIG. 2 is another perspective view of the package for container of FIG. 1.

FIG. 3 is a front view of package for container of FIG. 1. FIG. 4 is a rear view of the package for container of FIG. 1. FIG. 5 is a side view of the package for container of FIG. 1. FIG. 6 is an opposing side view of the package for container of FIG. 1.

FIG. 7 is a top view of the package for container of FIG. 1. FIG. 8 is a bottom view of the package for container of FIG. 1.

FIG. 9 is an exploded perspective view of the package for container.

FIG. 10 is another perspective view thereof.

FIG. 11 is a front view thereof.

FIG. 12 is a rear view thereof.

FIG. 13 is a side view thereof.

FIG. 14 is an opposing side view thereof.

FIG. 15 is a top view thereof; and,

FIG. 16 is a bottom view thereof.

The dash-dot-dash lines in the figures demarcate boundaries of the claimed design. The dash-dot-dot-dash lines of FIGS. 1–4 and 9–12 indicate fold lines that form no part of the claimed design. The dashed lines of the figures depict environmental structure that forms no part of the claimed design.
